UNITED STATES PATENT OFFICE.

HULBERT SANNER, OF CHICAGO, ILLINOIS, ASSIGNOR TO LOTHAR EDERER, OF CHICAGO, ILLINOIS.

DISTRIBUTING SWITCH.

Application filed January 5, 1924. Serial No. 684,577.

My invention relates to improvements in distributing switches and circuit selectors and has for one object to provide a new and improved form of distributing switch and circuit selectors associated therewith whereby a switch operated by clockwork, electric or otherwise may be used to close selected circuits through a selector device. Another object of my invention is to provide a new and improved form of switch and selector mechanism which will be light, compact and easily manufactured. Another object is to associate a switch and a selector in a compact, easily assembled but conveniently separable unit. Other objects will appear from time to time in the specification and claims.

My invention is illustrated more or less diagrammatically in the accompanying drawings, wherein—

20 Figure 1 is a plan view with parts removed and parts in section;

Figure 2 is a section along the line 2—2 of Figure 1;

25 Figures 3 and 4 are perspective views of contact fingers;

Figure 5 is a section along the line 5—5 of Figures 3 and 4;

Figure 6 is a blank from which the contact fingers are formed;

30 Figure 7 is a plan view of a modified form with parts removed;

Figure 8 is a section along the line 8—8 of Figure 7 with the contact arms in position;

35 Figure 9 is a blank on an enlarged scale from which the contact fingers shown in Figures 7 and 8 are formed;

Figure 10 is a perspective view of one of the contact fingers;

40 Figure 11 is a section along the line 11—11 of Figure 10;

Figure 12 is a section along the line 12—12 of Figure 10.

Like parts are indicated by like characters throughout the drawings and specification.

45 A is an insulating supporting panel. It is provided with a series of concentric spaced perforations A¹, A². These perforations contain the cylindrical tubular shanks A³, A⁴ of U-shaped contact bars A⁵, A⁶ some of which are notched at two points on their sides at A⁷. All the shanks for these contact bars are of the same diameter but the shanks A³ are longer than the shanks A⁴, the dis-

tance between the two arms of the U is 55 greater in the contact bars A⁶ than in A⁵. A⁸ is an annular insulating plate which overlies the lower arm of the U of each of the bars A⁶. This plate is apertured in line with the perforations A² so that the shanks 60 A³ may pass through. A⁹ is a second insulating plate which overlies the under arm of the U, A⁵. These contact bars or fingers are all of them arranged radially out of contact with one another and the two banks 65 are insulated and held in place by the two annular insulating discs.

B, B are annular supporting rings arranged above and below the banks of contact fingers. They are insulated from the 70 contact fingers by insulating rings B¹ and there is associated with each contact finger a contact ring B² insulated from it by an insulating ring B³. This entire assembly is held together by bolts B⁴ which pass through 75 the notches between adjacent pairs of contact fingers A⁶. A sleeve B⁵ carries the tension on the bolt and holds the parts together as a unit. B⁶ is a spider mounted on these bolts and having a central operating hub B⁷. 80 B⁸ is a clock shaft rotatable in the base A at one end and extending out through the hub B⁷. This clock shaft carries rotatable thereon a sleeve B⁹, which sleeve rotates in the bearing B⁷.

85 C is a bifurcated spring contact finger mounted on the shaft B⁸ and insulated therefrom. The width of the contact finger is substantially equal to the width of any one of the terminals or contact bars and as this 90 finger rotates with the shaft B⁸, it maintains constant contact with the contact ring B² and the contact fingers A⁵ and closes a circuit between them. C¹ is a similar bifurcated contact finger mounted on the sleeve 95 B⁹ which operates in the same way, the idea being that the shaft B⁸ and the sleeve B⁹ will be given an hour and minute motion. The upper bank will represent the minutes and there will be sixty fingers in that bank, 100 the lower bank will represent hours, there being twenty-four in that, but the hour and minute arrangement might be reversed or a decimal system or any other system might be used.

105 The contact ring B² has associated with it a conductor D which leads to any suitable electric circuit not here shown. The con-

fact fingers A^6 are made from the blank D^1 , the lower enlarged portion D^2 being rolled to form the shank A^4 , the long other portion being bent along the lines D^3 , D^4 to the shape indicated in Figure 3. The contact fingers A^5 shown in Figure 4 are made in the same manner from similar blanks but of different proportions.

Associated with this device is a selector which comprises an end plate E , alternate conductor plates E^1 and insulator plates E^2 , a central holding bar E^3 and a series of peripherally arranged conductor bars E^4 . The conductor plates E^1 are peripherally notched, there being a bar E^4 in line with each notch in each plate, the notches being arranged in line so that the spring contact fingers E^5 may be positioned along the bar E^4 and thrust it into the notch in any one of the insulating plates. Insulating tubes E^6 pass through perforations in the plates and contain conductors E^7 , there being one conductor for each plate and such conductor terminating at the plate and being altogether out of contact with the others. The result of this arrangement is that there are conductors E^7 and E^4 arranged in concentric rings projecting beyond the plate. When the projection is positioned by the bar E^4 and by the unequally spaced concentric pins E^8 arranged to insure proper angular relation, each of the conductors E^4 and E^7 engages one of the shanks A^3 , A^4 to close a circuit between a plate and two of the pairs of conductor fingers subject to the sleeve closure made by the spring finger. The wires D may lead to a bell ringing apparatus or anything of that kind and it is possible to select the time at which the bell will ring by positioning the spring finger E^5 . The bifurcated contact switches will go round and round but nothing will happen until such time as the two fingers engage the two contact fingers associated in a circuit which had been selected by the spring on the conductor E^4 when a circuit will be closed and a bell will ring or other signal will operate.

In the modified form shown in Figures 7 to 12 inclusive, the contact fingers are made from blanks having a narrow end finger forming portion Q , a wider tube forming portion Q^1 , and laterally extending wing portions Q^2 , bent to form the tube Q^3 , finger Q^4 , and U -shaped member Q^5 . These contact fingers are located in two concentric groups of holes in the supporting plate Q^6 , the U -shaped portion Q^5 engaging slots Q^7 so that the fingers are always radially positioned. The fingers of the inner group Q^8 are shorter than the fingers Q^4 . These fingers are adapted to be engaged by split spring contact arms R , R^1 mounted respectively on the timing shaft R^2 and sleeve R^3 and insulated from it by insulating sleeves R^4 .

Contact slip rings R^5 are associated with each of these fingers and adapted to be engaged by wipers R^6 and R^7 on the binding posts R^8 , R^9 and associated with conductors R^{10} , R^{11} whereby the circuits may be closed. The relation between the selector elements and the fingers is the same in this case as in the preferred form.

It will be evident that while I have shown in my drawings an operative device, still many changes might be made in the size, shape and disposition of parts without departing materially from the spirit of my invention and I wish, therefore, that my showing be taken as in a sense diagrammatic.

I claim:

1. A contact finger comprising a flat U -shaped body and an integral hollow sleeve perpendicular to one arm of the U .

2. A contact bank comprising a plurality of U -shaped contact fingers, flat supporting plates arranged on opposed sides of the contact arm of the U , means for holding the plate in position and for holding the contact fingers and the plates as a unit in position.

3. A contact bank comprising a plurality of U -shaped contact fingers, flat supporting plates arranged on opposed sides of the contact fingers of the U , means for holding the plate in position and for holding the contact fingers and the plates as a unit in position, and a plurality of separate short contact fingers, one associated with but insulated from each of the U -shaped fingers.

4. An electric distributor comprising an annularly arranged group of contact fingers, a contact ring insulated from and arranged adjacent said fingers and a wiper adapted to travel along the contact fingers and selectively close a circuit between one finger of the group and the ring, the fingers being U -shaped and having each a hollow cylindrical shank associated with the arm of the U which is not adapted to be engaged by the wiper.

5. An electric distributor comprising an annularly arranged group of contact fingers, a contact ring insulated from and arranged adjacent said fingers and a wiper adapted to travel along the contact fingers and selectively close a circuit between one finger of the group and the ring, the fingers being U -shaped and having each a hollow cylindrical shank associated with the arm of the U which is not adapted to be engaged by the wiper, conductors adapted to removably engage each one of the shanks and a conductor in permanent engagement with the contact ring.

6. An electric distributor comprising an annularly arranged group of contact fingers, an insulated supporting base for the group, there being a hollow tubular conductor shank associated with each finger of the group and a wiper adapted to engage successively fin-

gers at a point removed from the shank, a selective conductor adapted to be removably engaged with the shank.

7. A contact bank comprising an insulated base, a plurality of groups of contact fingers, tubular shanks associated one with each finger penetrating the supporting base, insulating plates adapted to hold the shanks and fingers in position with the fingers themselves radially disposed about a common center on the base, the insulating plates separating the fingers in two separate insulated concentric groups.

8. A circuit selecting device comprising in combination a selecting switch system including wipers and contact fingers, a manually adjusted selecting system adapted to be removably arranged with the switch system and means associated with the manually adjusted system for selecting individual circuits for operation.

9. The combination with a circuit selecting device comprising a plurality of insulated plates arranged side by side, a plurality of separate conductor bars arranged adjacent the peripheries of said bars and means interposed between the bar and the plate to close a circuit between them, of a switch assembly comprising a plurality of contact fingers, there being an electric connection between one contact finger and each bar and plate and wipers adapted to be moved across the fingers to close circuits to the bars and plates.

10. The combination with a circuit selecting device comprising a plurality of insulated plates arranged side by side, a plurality of separate conductor bars and means interposed between the bar and the plate to close a circuit between them, of a switch assembly comprising a plurality of contact fingers, there being an electric connection between one contact finger and each bar and plate and wipers adapted to be moved across the fingers to close circuits to the bars and plates, the circuit selecting device being removably associated with the switch assembly.

11. The combination with a circuit selecting device comprising a plurality of insulated plates arranged side by side, a plurality of separate conductor bars and means interposed between the bar and the plate to

close a circuit between them, of a switch assembly comprising a plurality of contact fingers, there being an electric connection between one contact finger and each bar and plate and wipers adapted to be moved across the fingers to close circuits to the bars and plates, the circuit selecting device being removably associated with the switch assembly, the switch fingers having hollow tubular shanks adapted to be yieldingly engaged by the conductor bars and there being conductor pins projecting one from each plate to engage other such tubular shanks.

12. A contact finger comprising a tubular shank open at both ends only, integral therewith a U-shaped extension having two arms tangential to the shank, a flat supporting strip projecting upwardly beyond the U in line with one side of the shank and a contact end integral with and bent at right angles to the supporting element.

13. In an electric distributor, an apertured supporting base, there being slots in the face thereof in line with the apertures, contact fingers having tubular shanks adapted to penetrate the apertures in the base and extensions adapted to engage the grooves in so the base.

14. In an electric distributor, an apertured supporting base, there being slots in the face thereof in line with the apertures, contact fingers having tubular shanks adapted to penetrate the apertures in the base and extensions adapted to engage the grooves in the base, and contact fingers extending upwardly from the shanks and bent at right angles to the axis thereof.

15. An electric distributor comprising an annularly arranged group of contact fingers, an insulated plate engaging them, a continuous conductor ring on the opposed side of the plate immediately adjacent the fingers having substantially the same inside diameter as the inside diameter of the group of fingers, a wiper adapted to travel along the fingers and ring, comprising a bifurcated member, one fork of which is in constant engagement with the ring, the other fork, of which is in engagement with the fingers.

Signed at Chicago, county of Cook and State of Illinois, this 20th day of December 1923.

HULBERT SANNER.
